CLAIM

The ornamental design for an insect repellent stick, as shown and described.

DESCRIPTION

FIG. 1 is a perspective view of an insect repellent stick, showing my new design;

FIG. 2 is a front elevational view, the rear being a mirror image thereof;

FIG. 3 is a left side elevational view thereof;

FIG. 4 is a right side elevational view thereof;

FIG. 5 is a top plan view thereof; and

FIG. 6 is a bottom plan view thereof.

FIG. 1-FIG. 5-FIG. 6-FIG. 3-FIG. 2-FIG. 4-
